UNITED STATES PATENT OFFICE.

EDGARE SPENCER LACHMANN, OF CHICAGO, ILLINOIS.

METAL FENCEPOST.

1,349,575.

Specification of Letters Patent. Patented Aug. 17, 1920.

Application filed September 18, 1919. Serial No. 324,585.

To all whom it may concern:

Be it known that I, EDGARE SPENCER LACHMANN, a citizen of the United States, residing in the city of Chicago, county of Cook, and State of Illinois, have invented certain new and useful Improvements in Metal Fenceposts, of which the following is a specification, reference being had to the accompanying drawings, forming a part thereof.

The purpose of this invention is to provide an improved metal fence post adapted to be self-anchoring in the ground, and to be held more securely by its anchoring than like posts heretofore in use. It consists in the elements and features of construction shown and described as indicated in the claim.

In the drawings;

Figure 1 is a perspective view of the fence post having an anchoring base embodying this invention.

Fig. 2 is a direct or forward side elevation of the lower portion of the post comprising the anchoring elements.

Fig. 3 is a view similar to Fig. 2 showing the same invention applied to or embodied in a post of which the main element is a channel bar.

Fig. 4 is a similar view, partly sectional, showing the invention embodied in an I-beam post.

Fig. 5 is a similar view showing the invention applied to an angle bar post.

The post proper consists of the metal bar, 1, of any flangular or angular cross-section, having the several webs or flanges or certain of them beveled to sharpen the lower end of the post, for facilitating driving it into the earth.

The anchor device comprises two flat bars, 2-2, riveted to the stem flange of the T-bar as seen at 3 in Figs. 1 and 2 or to the outer sides of the side flanges of the channel bar post as seen in Fig. 3, or to opposite sides of one flange of an angle bar post as seen in Fig. 5, or to the opposite sides of the web of an I-beam post as seen in Fig. 4. In any of the forms both said bars, 2-2, are bent

outward so as to diverge upwardly from the flange or flanges or web to which they are secured, and from each other, at a wide angle, so that they are at an angle to each other from 40° to 60° and thereby at their upper ends are spread from said web, flange

or flanges of the post to which they are secured, from one-third to one-half their length measuring from the point at which they diverge from said web, flange or flanges. These bars, 2-2, are connected together and secured to the main post member by cross tie-bar, 4, which is riveted to the cross flange of the T-bar, or to the web of the channel bar or to the other flange of the angle bar, or to the opposite flange of the I-beam (as shown in the several figures showing these several forms of main post members), and are bent obliquely to the width of the bar at the ends to lap on to and be secured to the portions of the bars, 2-2, to which the cross bar is riveted as seen at 6.

The purpose and operation in practice of this construction is, that when the post is driven into the ground, the earth forced aside by the diverging bars, 2-2, readily returns to the inner side of those bars on both sides, reentering from the one side freely between said bars and the stem flange of the T, and from the other side through the triangular openings, 7-7, which, by reason of the proportions of the several parts, are relatively large and permit free entrance of the earth through said openings, as well as above the cross bar. The "earth-wound," as it may be called, produced by the driving in of the post, is thus self-healing by the normal falling in of the earth through the gap originally produced by the diverging bars, 2-2, and the earth quickly becomes loaded between and upon these bars, causing them to effect a very secure anchorage of the post in the earth. The breadth of the diverging anchor bars, 2-2, as well as the loading of these bars by the earth which enters between them, tends strongly to oppose deflection of the post in the direction of the length of the fence; and the breadth of the cross bar added to the breadth of the cross flange of the T-bar and the corresponding flange or web in the other forms, strongly resists deflection of the post laterally with respect to the fence.

I claim:

An anchored metal fence post of which the main post member consists of a metal bar having a plurality of longitudinally extending flanges angularly disposed with respect to each other; anchoring elements consisting of bars secured to opposite surfaces

of certain of said flanges and bent divergently upward and outward at a wide angle, and a cross-tie-bar connecting the upper and wide spread ends of said anchor elements secured to another flange or web of the post member, the dimensions of the parts being such as to produce relatively

large triangular apertures between the post member and the tie-bar.

In testimony whereof, I have hereunto ¹⁰ set my hand at St. Paul, Minnesota, this 13 day of September, 1919.

EDGARE SPENCER LACHMANN.
